UNITED STATES PATENT OFFICE.

KENNETH S. BAXTER, OF MICHIGAN CITY, INDIANA, ASSIGNOR TO SHEET STEEL PRODUCTS COMPANY, OF MICHIGAN CITY, INDIANA, A CORPORATION OF INDIANA.

VEHICLE SASH DOOR.

Application filed October 15, 1920. Serial No. 417,110.

To all whom it may concern:

Be it known that I, KENNETH S. BAXTER, a citizen of the United States, and resident of Michigan City, county of LaPorte, and 5 State of Indiana, have invented certain new and useful Improvements in Vehicle Sash Doors, of which the following is a specification, and which are illustrated in the accompanying drawings, forming a part 10 thereof.

The invention relates to sash doors with special relation to doors of vehicles and has as an object the provision of a simple form 15 of door in which the sash may be lowered and in which the glass, as well as the sash as a whole, will be prevented from rattling.

An illustrative embodiment of the invention is shown in the accompanying drawings, in which

20 Fig. 1 is a front view of a completed door with the sash raised;

Fig. 2 is a vertical section on line 2—2 of Fig. 1;

25 Fig. 3 is a front view of a sash from the exterior;

Figs. 4, 5 and 6 are detail sections on the corresponding lines on Fig. 3, but drawn to an enlarged scale, and

30 Fig. 7 is a detail section drawn to an enlarged scale taken on line 7—7 of Fig. 1, showing the sash in a lowered position.

The sash 10 is shown in Figs. 3 to 6 as 35 formed of two sheet metal frames 11, 12, each having a flange 13 and 14 extending at a right angle from its outside edge at each margin. One flange, as 14, is designed to telescope within the other flange, as 13, to produce the complete sash frame. The inner margins of each frame are deflected in- 40 wardly at an angle, as at 15, 16, to make contact with the glass 17. The frames, 11, 12, are shown as secured together by screw fastenings 18, comprising an exteriorly threaded machine screw 19 and an interiorly threaded nut 20, both projecting within the frame and preferably having their heads countersunk as by inward deflection of the material of the frame about the screw holes. The head of both the screw and the 45 nut is slotted for coaction with a screw driver.

To hold the glass 17 in position, soft rubber cushions 21 and 22 are utilized. These cushions are made large enough to require squeezing into place and therefore exert

pressure on the edges of the glass from each direction. The cushions 22 are pierced for passage of the screw fastenings 18. To prevent rattling of the sash in the door the cushions 21 have a substantially semispherical knob 23 projecting from one side and a concave depression 24 in the other. Holes 25 are formed in the frame 12 through which the knobs 23 project when the sash is assembled. The depressions 24 allow the 50 knobs 23 to be pressed inwardly to a greater extent than the elasticity of the mass of the cushion 21 would itself permit.

To retain the sash 10 in its raised position and to press the bottom of the sash outwardly so that the lower knobs 23 will be pressed against the inner surface of the door panel 26, outwardly sloping lips 27 are provided which may be struck out from the material of the sash frame member 12. As 55 shown at 28, each of the margins of the window opening 29 in the door 30 are turned slightly inward. When the sash 10 is raised the lips 27 seat over the lower margin of the window opening and urge the sash outward. The projection of knobs 23 is greater than the inward deflection of the side margins 28 of the window opening and these knobs will therefore cushion the sash with- 60 in the door.

The door 30 may be constructed as disclosed in an application for cab door, filed by myself of even date herewith, and having Serial No. 419,108, filed Oct. 15, 1920. To hold the top of the sash in place out- 65 wardly against the inner surface of the outer panel 26, spring clips 31 may be secured, as by rivets, to the top member of the door frame. The clips 31 are formed with outwardly turned tips 32 behind 70 which the sash 10 may be forced when it is raised. A handle 33 is secured to the inner side of the upper portion of the sash. As shown, the handle has a downwardly and outwardly sloping margin 34 75 adapted to hook over the upper margin of the inner panel 35, forming the inner lower margin of the window opening, when the sash is lowered, as shown in Fig. 7.

A piece of angle iron 36 is secured to the inner surface of the panel 26 for increased stiffness. Spring clips 37, similar to clips 31, are secured to the panel above the angle iron 36 to press the sash with the cushion knobs 23 outwardly against the panel when 80 85 90 95 100 105 110

the sash is lowered. The space between the lower margin of the window opening 29 and the upper margin of the inner panel 35 must be sufficient to allow the lips 27 to pass in the rear of the margin 29 after slightly lifting the sash, in order that the sash may be lowered.

I claim as my invention:—

1. A sash comprising, in combination, spaced sash members adapted to be pressed against opposite sides of a pane of glass, one of said members having a hole therein, a cushion member adapted to form a seat for the edge of said glass, a knob on said cushion projecting through said hole, to cushion the sash against lateral jars.

2. A sash comprising, in combination, spaced sash members adapted to be pressed against opposite sides of a pane of glass, one of said members having holes in some of its sides, cushion members between said sash members adapted to act as seats for the edges of said pane of glass, knobs on some of said cushions projecting through said holes, others of said cushion members having holes therethrough and clamping

devices passed through said last named cushion members and through the sides of said frame members.

3. A sash comprising, in combination, a frame, a pane of glass mounted in said frame, an outwardly and downwardly projecting wing on the lower rail of said frame adapted to seat upon the lower edge of a window opening when the sash is raised and an outwardly and downwardly projecting wing on the upper rail of said frame adapted to seat upon the lower edge of the window opening when the sash is lowered.

4. A sash comprising, in combination, a frame, a pane of glass mounted in said frame, an angle plate having the upper portion of one of its parts secured upon the upper rail of said frame and the lower portion thereof projecting outwardly and downwardly to seat upon the lower edge of the window opening when the sash is lowered, the other part of the angle plate projecting outwardly from the upper edge of the first mentioned part to serve as a handle for raising the sash.

KENNETH S. BAXTER.
